UNITED STATES PATENT OFFICE.

DELBERT A. MILAM, OF CHARLESTON, WEST VIRGINIA.

ACETYLENE GENERATOR.

Application filed July 22, 1924. Serial No. 727,572.

To all whom it may concern:

Be it known that I, DELBERT A. MILAM, a citizen of the United States, residing at Charleston, in the county of Kanawha and State of West Virginia, have invented certain new and useful Improvements in Acetylene Generators, of which the following is a specification, reference being had to the accompanying drawings.

10 This invention relates to the structure of an acetylene generator to be used as a starting charge forming device for internal combustion engines and has for a particular object thereof the provision of a simple 15 and readily applied means for forming a highly combustible gas for injection in the intake manifold to assist in starting the engine.

A further object of the invention is to 20 provide a device of this character which is so constructed that the parts thereof are readily separable to permit cleansing of the device or supplying of the device with the ingredient with which the charge is formed.

25 A still further object of the invention is to provide a device of this character in which means is provided for storage of surplus gas not utilized in the starting operation.

30 These and other objects I attain by the construction shown in the accompanying drawings, wherein for the purpose of illustration is shown a preferred embodiment of my invention and wherein:

35 Figure 1 is a side elevation showing apparatus constructed in accordance with my invention applied to an internal combustion engine;

Figure 2 is an enlarged sectional view 40 through the apparatus showing the construction thereof;

Figure 3 is a section on the line 3—3 of Figure 2;

Figure 4 is a section on the line 4—4 of 45 Figure 2;

Figure 5 is a perspective of the holding bracket of the carbide generator and water tank;

Figure 6 is a perspective of the storage 50 tank bracket.

Referring now more particularly to the drawings, the charge forming device proper consists in apparatus embodying upper and lower casings 10 and 11, the upper casing

55 having upon its bottom a threaded flange 12 for coaction with an upstanding similarly

threaded flange 13 formed upon the open upper end of the lower casing 11. The lower casing 11 forms a carbide chamber while the upper chamber 10 forms a water 60 chamber.

Extending through and secured to the upper and lower walls of the upper chamber 10 is a sleeve 14, the upper end of

which extends above the upper end of the 65 casing and the lower end of which extends considerably below the lower end thereof. This sleeve is provided within the casing 10 and adjacent the bottom wall 15 thereof with an outlet opening 16 through which 70 water contained within the casing 10 is passed through the sleeve into the casing 11.

Slidably mounted within the bore of the sleeve is a plunger 17, the upper end of

which is of the same diameter as the bore 75 of the sleeve and the lower end of which is of a reduced diameter as indicated at 18.

Threaded upon the lower end of the reduced portion of the plunger 17 is a nut 19, upon the upper surface of which rests a washer 80

20 adapted to contact against the lower end of the sleeve 14 and when in contact therewith seals the lower end of the sleeve against the passage of water therethrough. The plunger 17 is of a length greater than the 85

length of the sleeve and the upper end thereof has threaded thereon a nut 21 forming a seat for one end of a spring 22 which surrounds the upper end of the plunger 17 and abuts the upper end of the sleeve so 90

that the plunger is urged upwardly thereby and the washer 20 kept normally in engagement with the lower end of the sleeve to seal the same. When the plunger 17 is in

its normal position the lower end of the 95 enlarged portion thereof is positioned immediately above the opening 16 of the sleeve

14 so that while the plunger is in this position water may enter the sleeve and fill the space about the reduced portion of the 100 plunger but may not escape from the sleeve because of the action of the valve at the lower end of the sleeve formed by the nut

19 and washer 20. The upper end of the chamber 20 is provided with means whereby 105 water may be introduced thereto as indicated at 23.

The numeral 24 designates an air intake conduit, one end of which is directed through the side wall of the water chamber 110 10 and sealed to this wall, the projecting end thereof being fitted with a valve 25.

The opposite end of the conduit 24 is directed through the bottom wall 15 of the chamber 10 interiorly of the threaded flange 12 of this bottom and has its extremity coiled, as at 26, and provided with a plurality of small openings 27. The numeral 28 designates a gas outlet conduit which has one end projected through the side wall of the chamber 10 and the projected portion of this 10 end being provided with one member of a union 29. The opposite end of the conduit 28 is directed through the bottom wall 15 of the chamber 10 and sealed thereto and is provided with a coiled extremity 30 having 15 openings 31 therein permitting the passage of gas into the conduit. The second member of the coupling 29 is carried by one end of the conduit 30, which at its opposite end communicates with a storage tank 31 20 intermediate the upper and lower ends thereof. This storage tank has communicating therewith at its upper end an outlet 32 adapted for connection, as at 33, with the intake manifold 34 of an internal combustion engine, this outlet conduit being 25 valved as at 35. The lower end of the storage tank 31 has a drain valve 36 of any suitable character.

As a support for the compartments 10 and 11 I provide a vertical attaching bracket 37 having at its end a horizontal extension 38 provided with an opening for engagement with a securing element which is in turn engaged with any suitable support 39 as, for example, one of the cap bolts 39 upon the head of an internal combustion engine. At its upper end this support is provided with a clamping band 40 adapted to encircle and clamp upon the compartment 10 adjacent the upper end thereof. At its lower end this bracket is offset inwardly, as at 41, and is provided with a reduced clamping ring 42 which clampingly engages upon the exterior of the threaded flange 12 upon the bottom of the container 10. It will thus be seen that the carbide container 11 can be readily removed at any time without disturbing the container 10 for refilling. A vertically extending support rod 43 has its lower end secured to the clamping band 42 and its upper end secured to the clamping band 40, the extremity of the support 43 extending above the clamping band 40 and having pivoted thereto one arm 44 of a bent lever. The extremity of this arm extends over the upper end of the plunger 17 and has an enlarged portion 45 for contact therewith. The opposite end of this lever has connected thereto an operating element 46 which preferably extends to the dash of the vehicle. As a means of supporting the storage tank 31 we provide a vertically extending bracket 47 having openings 48 through which securing elements may be directed for securing the bracket to the dash.

of the vehicle. This bracket has mounted thereon at vertically spaced intervals a plurality of spaced clamping bands 49 for engagement with the walls of the storage tank 31. 70

In the use of the device when it is desired to start the engine the operating element 46 is actuated to cause depression of the plunger 17. This depression of the plunger opens the lower end of the sleeve 14 and closes the opening 16 because of the fact that the enlarged portion of the plunger 17 is brought into alignment with this opening thus permitting only a certain amount of water to pass to the carbide chamber 11 for contact with the carbide C contained therein. This contact causes the formation of gas and as soon as the water has been released the starter is actuated or the engine otherwise brought into operation to cause suction within the intake manifold 34 which will cause this charge to be drawn through the storage tank 31 into the manifold of the engine. After the engine has started the valves 35 and 25 may be closed so that the carbide gas formed within the container 11 will be deposited in the storage tank 31 under pressure. When it is again desired to start the engine this extra carbide gas may be employed for starting the same. The arrangement of the inlet and outlet of the tank 31 prevents passage of water which may be contained in the gas to the intake manifold of the engine and causes its collection in the tank 31 from which it may be withdrawn from time to time by means of the drain cock 36. It will be obvious that the structure hereinbefore set forth is capable of a considerable range of change and modification without in any manner departing from the spirit of my invention and I accordingly do not limit myself to such specific structure except as hereinafter claimed.

I claim:—

1. In an acetylene gas generator, upper and lower containers, the upper container being provided upon the lower end thereof with a cylindrical interiorly threaded flange, the lower end of said container having a threaded neck coacting with said flange, means opening through the bottom of the upper container for permitting the passage of fluid from the upper container to the lower container, an air inlet and a gas outlet for the lower container, means for controlling the passage of fluid from the upper to the lower container comprising a sleeve directed through the top and bottom walls of the upper container, said tube having an opening therein adjacent the bottom of the upper container, a plunger mounted within said tube having its upper portion of the same diameter as the bore of the tube and its lower portion of less diameter than the

bore of the tube, a valve mounted upon the lower end of the plunger and coacting with the lower end of the tube to normally seal the same, the upper end of the plunger having an enlargement, and a spring extending between the upper end of the tube and the enlargement and normally maintaining the valve in engagement with the lower end of the tube, the lower end of the enlarged portion of the plunger being disposed immediately above the opening of the tube when the valve is engaged with the lower end of the tube.

2. In an acetylene gas generator, a water chamber, a carbide chamber, an outlet for

the carbide chamber and a measuring valve comprising a tube communicating with the water chamber and with the carbide chamber and a member operating within the tube having spaced valves one of which normally closes the communication between the tube and the carbide chamber, the other of said valves closing the communication between the water chamber and the tube upon operation of the member to open the valve controlling communication between the tube and the carbide chamber. 20
25

In testimony whereof I hereunto affix my signature.

DELBERT A. MILAM.
